UNITED STATES PATENT OFFICE.

CLINTON O. HARRINGTON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

METHOD AND APPARATUS FOR ADJUSTING ARMATURES OF ELECTROMAGNETIC DEVICES.

1,308,585.

Specification of Letters Patent.

Patented July 1, 1919.

Application filed January 17, 1917. Serial No. 142,818.

To all whom it may concern:

Be it known that I, CLINTON O. HARRINGTON, a citizen of the United States, residing at Edgewood borough, in the county of Allegheny and State of Pennsylvania, have invented certain new and useful Improvements in Methods and Apparatus for Adjusting Armatures of Electromagnetic Devices, of which the following is a specification.

This invention relates to electromagnets, and has for its object the provision of a method and apparatus for adjusting the armature of an electromagnet to give a predetermined torque to the armature when the electromagnet is supplied with a current of a predetermined potential and the armature is in the closed position, whereby the proper functioning of the armature will be insured.

Other objects of the invention will appear from a consideration of the following detailed description, taken in connection with the accompanying drawings forming a part of this specification, with the understanding, however, that the embodiment illustrated, though practical, is by no means the only embodiment which the invention may assume, wherefore the invention is not confined to any strict conformity with the showing of the drawings, but may be changed and modified in various particulars within the scope of the appended claims.

In the drawings, Figure 1 is a view showing, in rear elevation, one form of electromagnet having applied thereto one form of apparatus embodying my invention, such apparatus being diagrammatically shown in part. Fig. 2 is a vertical sectional view taken on the line II—II of Fig. 1.

Similar reference characters refer to similar parts in each of the views.

Referring to the drawings in detail, my invention as here shown is applied to an electromagnetic device M, comprising two windings W and W' mounted on cores C and C' respectively, the lower ends of the cores being formed with enlarged portions F and F' respectively, which constitute pole pieces. The upper ends of the cores C and C' are reduced in diameter to pass through holes in a back strap S, and are threaded to receive nuts 10 and 10' respectively, where-

by the back strap S and the windings W and W' are retained upon the cores. The electromagnet also includes an armature A which is pivotedly connected thereto by means of brackets 11, 11 secured to the pole pieces F and F'.

As here shown, the electromagnet is energized by means of a battery B connected to the windings W and W' through the medium of a rheostat R and a pole-changer P, the consequent energization creating a magnetic flux in the magnetic circuit to cause the armature A to be attracted to the pole pieces F, F', as will be understood. The movement of the armature A toward the pole pieces may be limited, so as to vary the closed position of the armature, by means of a screw X, which passes through a threaded hole in a bridge bar 12. The bar 12 is formed of non-magnetic material, such as brass or the like, and as best seen in Fig. 1 connects the cores C and C' at a point between the windings W and W' and the pole pieces F and F', the opposite ends of the bar being formed with suitable openings to receive the cores. The medial portion of bar 12, adjacent its forward edge, is provided with a threaded opening to receive the screw X, such screw having its lower end rounded for engagement with the armature A. Mounted upon the screw at the underside of the bar 12 is a nut 13 which is designed to coact with the bar to lock the screw in adjusted position, as will be understood.

From this construction, it is evident that by adjusting the screw X vertically within the bar 12, the closed position of the armature A with respect to the pole pieces F and F' will be accordingly varied.

G designates a galvanometer of a suitable construction which is electrically connected to a coil of wire Y by means of conductors 15, 15, such coil Y being shown in this instance surrounding a portion of the armature A.

It will, of course, be understood that the torque exerted on the armature at any time is proportional to the magnetic flux flowing therein. I will assume that it has previously been determined by experiment what the throw of the galvanometer needle should be for the desired torque on the armature at the predetermined energization of the electro-

magnet. The method of using the apparatus for the adjustment of an armature is then as follows:

The rheostat R is first adjusted to give the predetermined current value in the magnet windings as determined by an ammeter. The screw X is then adjusted to a point which the operator thinks may be approximately correct, and, while the armature A is held in contact with the screw by hand or otherwise, the pole-changer P is suddenly reversed and the throw of the galvanometer needle is noted. If the throw is greater than the proper value, the screw X is turned down to give a larger air gap between the armature and the pole-faces when the armature is in contact with the screw; if the throw is less than the proper value, the screw is turned up to reduce this air gap. The process is repeated until the galvanometer throw is the proper value upon reversal of the pole-changer, and when the proper adjustment of the screw is secured it is locked in such position by the nut 13. It will then be known that when the electromagnet is energized at the proper current value and the armature is in engagement with the screw X, the desired torque will be exerted on the armature. This desired torque can thus be secured irrespective of any irregularities in the magnetic circuit such, for example, as unevenness of the pole faces or of the armature, or additional reluctance at the junction of the back strap with either core.

My invention is of particular advantage in connection with electromagnetic relays wherein contacts are operated by the armature A. In such instance the pressure exerted on the contacts when the armature is closed will be the desired value regardless of irregularities in the magnetic circuit, provided the electromagnet is energized at the predetermined current value. My invention is not, however, limited to electromagnetic relays, but is applicable to any electromagnet regardless of the means controlled or operated by the armature.

Copies of this patent may be obtained for five cents each, by addressing the "Commissioner of Patents, Washington, D. C."

Having thus described my invention, what I claim is:

1. An apparatus of the character described, comprising an electromagnet including an armature, a source of current for said electromagnet, means for varying the flow of said current as supplied to said electromagnet, means for determining the magnetic flux in the magnetic circuit of the electromagnet, and means for adjusting the closed position of said armature. 50 55

2. An apparatus of the character described, comprising an electromagnet including an armature, a source of current for said electromagnet, means for determining the magnetic flux in said armature, and means for adjusting said armature to cause the 60 65 armature to carry a predetermined flux at a given energization of the electromagnet when the armature is in closed position.

3. The method of adjusting an armature with relation to an electromagnet so that 70 when the armature is in the closed position a given energization of the magnet will cause a predetermined pull on the armature, which consists in supplying a given current to the magnet, measuring the magnetic flux produced thereby in the armature, and adjusting the closed position of the armature to such location that the flux in the armature has a predetermined value. 75

4. The method of adjusting an armature 80 with relation to an electromagnet so that when the armature is in the closed position a given energization of the magnet will cause a predetermined pull on the armature, which consists in supplying a given current to the 85 magnet, measuring the magnetic flux produced thereby in the magnetic circuit, and adjusting the closed position of the armature to such location that the flux in said magnetic circuit has a predetermined value. 90

In testimony whereof I affix my signature in presence of two witnesses.

CLINTON O. HARRINGTON.
